PACKING STAND

Reuben B. Robertson, Fort Lauderdale, Fla.

Application May 2, 1951, Serial No. 224,180

7 Claims. (Cl. 155—41)

1

This invention relates to an improvement in an article of furniture and has particular reference to a packing stand for use in packing suitcases, wardrobe cases or the like.

It is the purpose of the present invention to provide a packing stand, similar to the conventional luggage benches, to serve jointly as a seat or as a means for maintaining the closure cover of a suitcase or the like open during the process of packing or unpacking and embodies new and novel means associated with a seat panel, whereby the seat panel will be held open and means be exposed behind which the suitcase cover is to be positioned to be held in open position during the packing, after which, the cover holding means shall be recessed into the panel and the panel swung to seat forming position.

Novel structural details will be more clearly set forth in the following description, reference being had to the accompanying drawing, wherein is illustrated a preferred form of the invention and wherein like characters of reference are employed to denote like parts throughout.

In the drawings:

Figure 1 is a perspective view of a packing stand constructed in accordance with the invention.

Figure 2 is a perspective view of the stand in the open position.

Figure 3 is a fragmentary perspective view of the stand in the open position, with parts shifted to the operative supporting angle.

Figure 4 is a transverse section taken on line 4—4 of Figure 3, and

Figure 5 is a horizontal section on line 5—5 of Figure 2.

Referring specifically to the drawings, the numeral 5 designates a generally rectangular frame, carrying a top panel 6, that is recessed over its major area for the reception of a resilient pad 7, formed of rubber or other suitable material. The frame 5 is supported upon legs 8, in a customary manner.

Hinged, as at 9, is a seat panel 10, rectangular in shape and having a dimension slightly less than the frame 5, whereby its marginal edges lie inwardly of and identically spaced from the marginal edges of the frame. The seat panel 10 is preferably upholstered or covered upon its normal exposed outer surface by fabric, plastic or the like and in any desirable color. The seat panel swings upward to a vertical position and is limited in its swinging movement upwardly to the vertical position by any suitable stop device indicated at 10a, in which position it will

be securely held against accidental closing, by a wing device, to be later described.

The inner face of the seat panel, adjacent one end, is recessed, as at 11, for the seating reception of a wing device, illustrated as a whole by the numeral 12. Two edges of the wing 12 are formed upon a right angle, with one vertical edge being hinged to the inner face of the seat panel whereby the wing shall swing into and out of the recess 11 and, when fully engaged within the recess, to be wholly flush with the inner face of the seat panel. The panel is held in the recessed position, by a suitable latch 13. The hinging 14 for the wing, disposes the wing to swing horizontally when the seat panel is shifted to the fully open or vertical position, with the wing serving as a brace to maintain the seat panel against accidental closing. The wing may be cut in any desirable ornamental curvature, as at 15, with the recess 11 being formed in an identical manner. A finger opening 16 is formed in the wing 12 to facilitate its swinging movement from the recess, whereby it shall be positioned at a right angle to the seat panel.

The wing 12 is further provided with spaced apart and identical openings 17, corresponding in shape to the recess 11, but on a relatively smaller scale. Hingedly supported within the openings 17, as at 18, are vertically swinging stop wings 19, for a purpose to be described. The wings 19 are adapted to swing downwardly to be disposed in horizontal planes to serve as a stop means, behind which the vertically swinging lids or covers of suitcases or wardrobe cases may be engaged to prevent them from falling down during the process of packing. The wings 19 are arranged at different elevations to accommodate baggage lids of varying sizes. The openings 17 extend entirely through the wing 12, while the wings 19 are of identical thickness with that of the wing 12 so that, when the wing 12 is to be collapsed and recessed, the wings 19 will be flush with both the inner and outer sides of the wing 12 and, when the wing 12 is recessed within the recess 11, all of the parts will lie in flush position with the inner face of the seat panel 10.

It has been found that wardrobe cases having extra long dimensions and with their lids opening upward from one end, have difficulty in retaining the lid open during packing operations and, since the stand is not normally sufficiently wide to accommodate such cases in a position whereby the lid may engage behind one of the wings 19, a third stop wing 20, hinged at 21,

to swing vertically to be disposed in a horizontal plane, is normally seated within a recess 22, cut in the recess 11 adjacent the top thereof. When the stop wing 20 is to be employed, the wings 19 are recessed into their respective openings. In using the wing 20, the wardrobe case is arranged longitudinally of the stand and its lid swung upward to a vertical position and the wing 20 then pulled outwardly to engage over the inner edge of the lid. The wing 20 normally lies flush with the inner face of the recess 11 to permit the full recessed position of the wing 12.

In the normal use the stand is employed in hotels or like rental units to serve both as a seat and as a luggage stand for packing and unpacking suitcases of the like. When a conventional suitcase is to be packed or unpacked, the seat panel 10 is swung upward and the wing 12 swung outwardly at right angles thereto, serving as a brace against the accidental swinging downwardly of the panel. For normally small suitcases, the lower wing 19 is swung inwardly to the dotted line position and the lid of the suitcase is shifted therebehind. The suitcase may then be packed or unpacked without the annoying continuous falling downwardly of the lid. For larger suitcases, the upper wing 19 is employed in a like manner. In using the wings 19, the suitcase is arranged transversely of the stand and rests upon the pad 7 and, since the pad extends slightly above the surrounding frame 5, the suitcase will be held out of contact with the frame and thus avoid scratching or marring of the luggage. When the long type of wardrobe cases are employed, that open from the end, the case is arranged longitudinally of the stand and the lid of the case is then swung upwardly and the wing 20 then swung downwardly to engage over the inner edge of the lid, thus securely holding the lid in the fully opened position during the packing or unpacking operation. When not in use, the several wings 19 and 20 are fully recessed and the wing 12 swung to fully recessed position within the recess 11 and latched therein by the latch 13, after which the panel 10 is swung downwardly, completely hiding the several wings and presenting an ornamental and practical seat or bench.

It will be apparent from the foregoing, that a very desirable improvement has been made upon the conventional luggage bench or seat. Much difficulty has been experienced by travellers in the packing and unpacking of luggage, since the lid is continually falling down, especially when the lid is supporting relatively heavy clothing and obviously is overbalanced. The improved bench seat panel is quickly swung upward and the wing 12 shifted outwardly to bracing position, after which the selected small wing swung to operative position. The device is shifted to operative and inoperative position in a minimum of time and is highly effective for the purposes designed. Further, the device is cheap to manufacture, is strong and durable and the structure may be embodied in various shapes and sizes of benches.

It is to be understood, that the invention is not limited to the precise construction shown, but that various changes in the shape, size and arrangement of parts may be resorted to as readily fall within the spirit of the invention or the scope of the subjoined claims.

Having described my invention, what I claim as new and desire to secure by Letters Patent is:

1. A luggage packing stand for supporting

and maintaining the hinged lids of luggage open, consisting of a leg supported frame having a resilient top covering, a seat panel hinged along one edge to the frame to swing in a vertical plane, a wing brace hingedly supported by the seat panel to swing horizontally when the panel is shifted to a vertical position, stop devices carried by the wing brace to be positioned in the path of swinging movement of the luggage lid and a stop device carried by the seat panel to be positioned in the path of swinging movement of the luggage lid, the stop devices being recessed in the wing brace and seat panel, and the wing brace being recessed in the panel.

2. A luggage packing stand for supporting and maintaining the luggage lid in open position, consisting of a leg supported frame recessed on its top to receive a cushion pad, the pad projecting above the top of the frame, a seat panel hinged at one edge to the frame and being coextensive with the pad, the panel being recessed on its inner face, a brace wing hingedly supported to the panel for flush engagement within the recess of the panel, the wing adapted to swing horizontally to brace the panel in open vertical position, stop wings recessed into the brace wing and hinged to swing vertically for being positioned at right angles to the brace wing, a stop wing recessed into the recess of the panel to swing vertically for extended position from the panel, the last named wing when recessed being flush with the inner surface of the panel recess, the first named stop wings when recessed being flush with the faces of the brace wing, the brace wing when recessed being flush with the inner face of the panel and latch means for retaining the brace panel in recessed position.

3. A combined seat and luggage packing stand that consists of a leg supported rectangular frame having an upper surface recessed, a resilient pad fixed in the recess and projecting above the frame, a seat forming panel that is coextensive with the pad and hinged along one longitudinal edge to the frame, the panel adjacent one end upon its inner face being recessed, a wing brace having a thickness corresponding to the depth of the panel recess and corresponding in shape to the panel recess for flush seating in the recess, the wing brace being hinged to the panel for swinging horizontally when the panel is shifted to a vertical position for positioning the brace at a right angle to the panel for bracing engagement with the pad, the wing brace provided with spaced openings therethrough, stop wings adapted to have a flush seating within the openings, hinge means supporting the stop wings to swing vertically for lateral positioning in the path of a lid carried by a suitcase supported upon the pad, the panel recess being further provided with a recess adjacent its upper end, a stop wing hingedly supported in the last named recess to normally lie flush with the surface of the panel recess, the last named stop wing adapted to swing vertically to be disposed in horizontal extended position from the panel to lie in the path of an open lid carried by a wardrobe case, the several stop wings and brace wing in the inoperative position being flush with their respective mounting to permit the seat panel to be swung to seat forming engagement with the frame and pad.

4. In a combined seat and packing stand for luggage, that consists of a rectangular frame having corner legs and a top, the top being re-

cessed and receiving a cushion pad that projects above the frame, a rectangular seat panel hinged along one longitudinal edge to the frame, the panel being coextensive with the pad and adapted to swing vertically, the inner face of the panel provided with a relatively large recess adjacent one end, the recess having two edges forming a right angle, a wing brace shaped to correspond to the panel recess and having a thickness corresponding to the depth of the panel recess whereby the wing will have a flush seating in the recess, hinges along one vertical edge of the wing to permit the swinging movement of the wing to a right angular position from the panel when in the vertical position, the wing provided with upper and lower identical openings each entirely therethrough with the openings each having edges forming a right angle, stop wings hingedly supported on the brace wing for vertical swinging movement for normal seating within the openings, the stop wings adapted to swing outwardly to be disposed at a right angle to the brace wing and in the path of swinging movement of an open lid of a suitcase, the stop wings being of identical thickness to the brace wing, the panel recess being further recessed for the reception of a stop wing that is positioned adjacent the upper portion of the recess, the last named stop wing being hinged to the panel to swing outwardly at a right angle to be disposed in the path of swinging movement of a lid of a wardrobe case, the last named wing in recessed position lying flush with the surface of the panel recess, the first named stop wings in recessed position being flush with both sides of the brace wing, the brace wing and its supported stop wings in recessed position being flush with the inner surface of the panel, a latch carried by the panel to shiftably engage and

retain the brace wing in recessed position, the brace wing provided with a finger hole.

5. In combination, a luggage packing stand having hinged collapsible means connected therewith adjacent one end thereof, shiftable stops connected with the collapsible means, the shiftable stops being positioned in the path of swinging movement of hinged covers of luggage articles supported on the stand and supporting the covers in open position.

10. 6. A luggage packing stand that embodies a leg supported frame having a seat panel hingedly supported thereon to swing to a vertical position, stop devices connected with the panel to be shifted to a position to lie in the path of movement of an open cover of a suitcase or wardrobe case when the panel is in the vertical position.

15. 7. A luggage packing stand that embodies a leg supported frame having a cushion top, a seat panel hingedly supported on the frame to swing to a vertical position, a wing device hinged to the panel to swing to a right angle thereto to brace the panel against downward swinging movement, shiftable stop devices carried by the wing device to be positioned in the path of swinging movement of the vertically disposed open lids of luggage cases.
